FLUID PRESSURE ACCUMULATOR

Application filed April 2, 1931. Serial No. 527,226.

This invention relates to a fluid pressure accumulator adapted to be incorporated as a part of a fluid pressure line which may be used for various purposes.

5 The object of the invention is to provide means for maintaining the required pressure under conditions where the pressure creating means temporarily may be inactive or may develop pressure at a slower rate than it is being used. It is also desirable to provide a relief or safety valve or port to prevent the possible loading of the accumulator beyond its capacity.

10 The invention, in its preferred form will be more particularly described in connection with the accompanying drawings, in which—

15 Figure 1 is a plan view of accumulator; Figure 2 is a vertical section taken on the line 2—2 of Figure 1; and

20 Figure 3 is a side elevation of the accumulator.

The invention, in its present adaptation has been devised particularly for use in actuating a hydraulic clutch, although it is obviously capable of use in any pressure line.

25 As illustrated in the drawings, the invention comprises a reservoir 5 having a cover 6 which is secured thereto by bolts 7 or other suitable means. While the system may be operated with a gaseous fluid, it is more positive in its action and more quickly responsive if the reservoir is partially filled with oil or other liquid, owing to the fact that liquids 30 are substantially incompressible. A conduit 8 leads through the cover 6 and is adapted to be connected to a pump which discharges through a conduit 9 into a cylinder 11 formed as a part of the cover 6. The conduit 8 is extended, as shown at 12, to the bottom part of 35 the reservoir and its inlet end is provided with a strainer 13.

40 A piston 14 is operable within the cylinder 11 and is urged upwardly by a coil spring 15 seated within a pocket 16 which constitutes the end of the cylinder and which is provided with a port 17 in its bottom and with lateral ports 18 above the normal level of the liquid within the reservoir.

45 50 As the liquid is pumped through the con-

duit 9 into the upper end of the cylinder 11, while pressure is not being used, the cylinder accumulates a supply of liquid which is subject to the pressure of the piston 14 under the influence of the compressed spring 15. 55 As the piston 14 is forced downwardly, an overload is prevented by relief ports 19 in the side of the cylinder, which allow the liquid to escape as they are uncovered and maintain the accumulator at its maximum capacity, as shown in Figure 2, until such time as the pressure line is used to operate a hydraulic clutch or other pressure operable device. A conduit 20 leads from the upper end of the cylinder to the point where the pressure is to be utilized and when the pressure operated device is released, the spent liquid is returned to the reservoir 5 through a conduit 21. 60 65

The reservoir 5 is adapted to be supplied with liquid through a filler mouth 10 and an air vent pipe 22 is provided in the cover 6 to permit variations in the level of the liquid within the reservoir.

70 75 When this accumulator is interposed in a pressure line, it permits the pump to operate continuously to build up or to accumulate liquid in the cylinder 11 so that the latter will be in condition to operate at its potential capacity, while the pump may be temporarily stopped or may be supplying pressure at a slower rate than it is to be utilized. This is of special importance in the operation of hydraulic clutches as used on power presses, since when a valve is turned to admit 80 oil from the conduit 20 to the clutch, the operation of the latter is not dependent upon the simultaneous operation of the pump. The pump may be driven only while the slide 85 is operating. While the slide is stationary, there is sufficient liquid in the cylinder 11 to throw the clutch into operative position as soon as the valve is actuated, and during the operation of the slide, the pump again fills 90 the cylinder 11 to its capacity.

95 100 While I have shown and described specifically one embodiment of the invention, it is apparent that the same may be considerably modified without departing materially from the scope of the appended claims.

What I claim is:—

1. A fluid pressure accumulator comprising a reservoir, a cover for said reservoir formed with a cylinder depending within the reservoir, said cylinder having an inlet and outlet through the cover, a head at the lower end of the cylinder having a vent, a piston within the cylinder, and an expansile spring between said head and the piston. 50
2. A fluid pressure accumulator comprising a reservoir, a cover for said reservoir formed with a cylinder depending within the reservoir, said cylinder having an inlet and outlet through the cover, a head at the lower end of the cylinder having a vent, a piston within the cylinder, and an expansile spring between said head and the piston, said cylinder having a relief vent adapted to be uncovered by said piston when moving in opposition to said spring before it strikes said head. 75
3. A fluid pressure accumulator comprising a reservoir, a cover for said reservoir formed with a cylinder depending within the reservoir, said cylinder having an inlet and an outlet through the cover, a head at the lower end of the cylinder and having a pocket with a vent therein, an expansile spring seated in said pocket, and a piston against which the spring bears. 80
4. A fluid pressure accumulator comprising a reservoir, a cover for said reservoir formed with a cylinder depending within the reservoir, said cylinder having an inlet and an outlet through the cover, a head at the lower end of the cylinder and having a pocket with a vent therein, an expansile spring seated in said pocket, and a piston against which the spring bears, said cylinder having a relief vent adapted to be uncovered by said piston when moving in opposition to said spring, before it strikes the head of the cylinder. 85
5. A fluid pressure accumulator comprising a reservoir, a cover for said reservoir formed with a cylinder depending within the reservoir, an outlet conduit extending through said cover from a point near the bottom of the reservoir outside of the cylinder, an inlet conduit leading into the reservoir outside of the cylinder, said cylinder having an inlet and an outlet through the cover, a head at the lower end of the cylinder having a vent, a piston within the cylinder, and an expansile spring between said head and the piston. 100
6. A fluid pressure accumulator comprising a reservoir, a cover for said reservoir formed with a cylinder depending within the reservoir, an outlet conduit extending through said cover from a point near the bottom of the reservoir outside of the cylinder, an inlet conduit leading into the reservoir outside of the cylinder, said cylinder having an inlet and an outlet through the cover, a head at the lower end of the cylinder having a vent, a piston within the cylinder, and an expansile spring between said head and the piston. 115
7. A fluid pressure accumulator comprising a reservoir, a cover for said reservoir formed with a cylinder depending within the reservoir, an outlet conduit extending through said cover from a point near the bottom of the reservoir outside of the cylinder, an inlet conduit leading into the reservoir outside of the cylinder, said cylinder having an inlet and an outlet through the cover, a head at the lower end of the cylinder having a vent, a piston within the cylinder, and an expansile spring between said head and the piston, said cylinder having a relief vent adapted to be uncovered by said piston when moving in opposition to said spring, before it strikes the head of the cylinder. 120
8. A fluid pressure accumulator comprising a reservoir, a cover for said reservoir formed with a cylinder depending within the reservoir, an outlet conduit extending through said cover from a point near the bottom of the reservoir outside of the cylinder, an inlet conduit leading into the reservoir outside of the cylinder, said cylinder having an inlet and an outlet through the cover, a head at the lower end of the cylinder having a vent, a piston within the cylinder, and an expansile spring between said head and the piston, said cylinder having a relief vent adapted to be uncovered by said piston when moving in opposition to said spring, before it strikes the head of the cylinder. 125

In testimony whereof I have hereunto signed my name to this specification.
